UNITED STATES PATENT OFFICE.

OTTO HOLZ AND PAUL HAERRY, OF SCHENECTADY, NEW YORK.

BAIT-MOVING DEVICE.

No. 798,344.

Specification of Letters Patent.

Patented Aug. 29, 1905.

Original application filed October 31, 1904, Serial No. 230,689. Divided and this application filed April 4, 1905. Serial No. 253,772.

To all whom it may concern:

Be it known that we, OTTO HOLZ and PAUL HAERRY, citizens of the United States, residing at Schenectady, in the county of Schenectady and State of New York, have invented certain new and useful Improvements in Bait-Moving Devices, of which the following is a specification.

The present application is a division of our prior application, Serial No. 230,689, filed October 31, 1904.

Our present invention relates to the specific form of a bait-moving device for fishing purposes and differs from our prior application in that it relates to a float that is propelled by the motor mechanism secured to or contained therein.

Another object of our invention is to control the path of travel of the bait-moving device or float—that is, when it is desired to propel the float in a circle the lateral displacement of one of the disk-carrying arms out of symmetry with the other will cause the desired effect to take place.

The bait-moving device comprises a float in which is mounted a stored-up energy device or motor which may consist of a casing inclosing a flat coiled spring, suitable gearing, and automatic means for arresting the movements of the gearing to which a propeller-shaft is secured for driving the float. The movements of the motor are controlled by the arms which carry the disks or balls of cork which raise the arms when the float strikes the water, due to their buoyancy, and disengage the pin or stop from the perforations in one of the gears of the motor mechanism, allowing the motor to drive the propeller-shaft. If the device is withdrawn from the water, the weight of the disks will bring the pin or stop into engagement with perforations in the gear-wheel, thereby arresting its further rotation and stopping the bait-moving device or float.

In the accompanying drawings, which form a part of this specification, Figure 1 is a vertical section of a float containing a motor arranged to be self-propelled forward or in a circle. Fig. 2 is a front elevation of the same. Fig. 3 is a plan view of the motor mechanism for driving the propeller-shaft; and Fig. 4 is a vertical section of the same, showing the stop mechanism or means for releasing the motor.

Referring now to the drawings, the two-part cork float 1 is divided centrally and se-

cured together by any suitable means, such as by winding bands of wire 2 around it near its ends. Inside the float a recess is provided to receive a motor-casing 3, and in this casing is secured a spring-motor 4. The stop mechanism and release device comprise a stop-lever 5, which is pivoted in a bearing 6 on the top of the casing 7. The lever 5 carries a pin 8, which registers with a circle of perforations in a gear-wheel 9 of the motor-gearing, so as to prevent the spring-motor from unwinding when not in use. Secured to the float at its bottom is a fin-keel 10, which tends to keep the float in an upright position. Journalled in the sides of the float are two adjustable arms 11, carrying disks or balls of cork which raise the arms when the float is lowered into the water, this operation moving the lever 5, to which they are secured, and thereby causing the pin or stop 8 to disengage from the perforations of the wheel 9, allowing the spring-motor to drive the shaft 12. This shaft rotates a propeller 13 at the rear end of the float. The bait is suspended from a rod 14 at the stern of the float.

An arbor 15 is mounted in the upper end of the motor-casing, and its end is squared to receive a key for winding the motor when it is run down. The adjustable arms 11 are provided with adjustable connections 16 to enable the float to be driven in a circular path, depending on the unequal lateral adjustment of the arms. If the arms are displaced symmetrically, the motor will propel the float in a straight path. The fishing-line is attached to the stud 17, which passes through the upper portion of the float. This stud is fastened to the motor-casing 7.

The operation of our device is as follows: The motor having been wound up, the float is lowered into the water. When the float comes in contact therewith, the adjustable arms that carry the disks or balls of cork are raised due to the buoyancy thereof, thus causing the pin or stop to disengage from the perforations of the wheel, allowing the motor to drive the propeller-shaft through gearing, moving the float to which the bait is attached. If the float is withdrawn from the water, the weight of the adjustable arms and disks will bring the pin or stop into engagement with the perforated gear-wheel, thereby arresting its further rotation.

In accordance with the provisions of the patent statutes we have described the principle of operation of our invention, together

with the apparatus which we now consider to represent the best embodiment thereof; but we desire to have it understood that the apparatus shown is only illustrative and that 5 the invention can be carried out by other means.

What we claim as new, and desire to secure by Letters Patent of the United States, is—

1. A bait-moving device, comprising the 10 combination of a float, a bait-suspending means, a motor, and means for controlling the path of travel of the float.

2. A bait-moving device, comprising the 15 combination of a float, a motor, and automatic means for controlling the operation of the motor and the path of travel of the float.

3. A bait-moving device, comprising the 20 combination of a float, a bait-suspending means, a motor, and automatic means for controlling the operation of the motor and the path of travel of the float.

4. In a bait-moving device, the combina-

tion of a float, a motor, a shaft, and a propeller on said shaft for driving the float.

5. In a bait-moving device, the combination 25 of a float, a bait-suspending means, a motor, a shaft, and a propeller on said shaft for driving the float.

6. In a bait device, the combination of a 30 float, a motor, a shaft, a propeller on said shaft for driving the float, and means mounted on the float for starting or stopping said motor.

7. In a bait device, the combination of a 35 float, a motor, a shaft, a propeller on said shaft for driving the float, and means mounted on the float for controlling its path of travel.

In witness whereof we have hereunto set our hands this 3d day of April, 1905.

OTTO HOLZ.
PAUL HAERRY.
